UNITED STATES PATENT OFFICE.

EDWARD J. SKINNER, OF NEW BRITAIN, CONNECTICUT, ASSIGNOR TO THE SKINNER CHUCK COMPANY, OF SAME PLACE.

DESIGN FOR A CHUCK.

SPECIFICATION forming part of Design No. 29,067, dated July 19, 1898.

Application filed May 3, 1898. Serial No. 679,634. Term of patent 14 years.

To all whom it may concern:

Be it known that I, EDWARD J. SKINNER, a citizen of the United States, residing in New Britain, in the county of Hartford and State 5 of Connecticut, have invented and produced a new and original Design for a Chuck, of which the following is a specification.

My invention relates to a design for the chuck hereinafter described and claimed.

10 In the accompanying drawing the figure is a perspective view of the base or rear of a chuck, showing the design.

15 My design is composed of a central hub, as A, a ring, as B, surrounding the same, and a web, as C, joining said hub and ring in such

a manner as to produce a depression or hollow between the two parts, and upon this web is represented two series of ribs, as 2 and 3, alternately of different widths and heights, respectively, and each rib extends radially 20 from the central hub A and connects the same with the ring B, and the ribs 2 are longitudinally slotted, as at 4.

What I claim is—

The design for a chuck, substantially as 25 shown and described.

EDWARD J. SKINNER.
